UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

FOLDING STAKE-POCKET.

1,123,143.

Specification of Letters Patent. Patented Dec. 29, 1914.

Application filed July 11, 1914. Serial No. 850,456.

To all whom it may concern:

Be it known that I, JOHN M. ROHLFING, a citizen of the United States, residing at the city of St. Louis, State of Missouri, have invented a certain new and useful Improvement in Folding Stake-Pockets, of which the following is a full, clear, and exact description, such as will enable others skilled in the art to which it appertains to make and use the same, reference being had to the accompanying drawings, forming part of this specification, in which—

Figure 1 is a front view of the preferred form of my invention with the loop member folded down against the side of the car. Fig. 2 is a side elevation of the same. Fig. 3 is a front view of a modified form. Fig. 4 is a side view of a second modified form. Fig. 5 is a side elevation of the form shown in Fig. 3. Fig. 6 is a detail of still another modified form. Fig. 7 is a top view of still another form. Fig. 8 is a front view of the same. Fig. 9 shows a front view of a sixth form. Fig. 10, a front view of a seventh form. Fig. 11, a side elevation of the same.

My invention relates to collapsible or foldable stake pockets for railroad cars, which are characterized by having the loop or pocket portion which embraces the stake, foldable back against the side of the car to which the pocket is attached, for the purpose of removing it out of the way of possible injury.

The purpose of my invention is to provide a very simple and strong form of stake pocket which may be manufactured very cheaply, and which may be readily attached to the car, and very easily and rapidly moved to its infolded or outfolded position.

In the preferred form of the invention which is illustrated in Figs. 1 and 2, it will be seen that my invention includes a pair of strap members 1, in this instance identical, formed of flat strip material and shaped to provide a pair of attaching ears 2, a supporting pocket 4 for holding the loop member in its outfolded position, and a retaining pocket 5 for supporting the loop member in its infolded position and permitting its movement to its outfolded position. The loop member 6 has outwardly directed extremities 7 which are engaged behind the strap members 1, and between these ex-

tremities is shaped so as to provide a loop 55 adapted to embrace the stake and hold it in position against the side of the car. In the preferred form, the loop member is made of flat strip material of proper dimensions, and the supporting pocket 4 is of the proper 60 depth to receive the extremities 7, and leaves just sufficient space between its inner face and the wall of the car to permit the extremities 7 to slip down thereinto when the loop member is swung outward to its horizontal 65 position. When the extremities 7 are so positioned in the supporting pocket 4, the loop member will be held in its horizontal position by contact with the inner face of the strap member 1 and the side of 70 the car. The retaining pocket 5 is sufficiently wide to receive the extremities 7 when the loop member is folded downwardly to a vertical position, and is of sufficient height to allow clearance for the 75 swinging of the loop member into its horizontal position. When the loop member is in its horizontal position, and it is desired to fold it back against the side of the car, it is first lifted so that the extremities 7 are 80 removed from the supporting pockets 4, and then allowed to swing downwardly, the greater breadth of the retaining pocket 5, permitting the extremities 7 to swing over.

In the modification illustrated in Figs. 3 85 and 5, the loop member 6 is of round bar material, and has its extremities turned upwardly at right angles to the general plane of the loop to provide supporting lugs 8. The strap members 1, instead of being 90 formed with two pockets of different widths, have but a single pocket of height somewhat greater than the diameter of the extremities 7 of the loop member. Somewhat above the middle of the pocket, the strap members are 95 broadened out to form retaining faces 9 which lie in the general vertical line of the lugs 8. When the loop 6 is in its infolded or vertical position, the extremities 7 are in the upper portion of the pocket, and the 100 lugs 8 rest on the shoulders formed by the tops of the retaining portions 9. To move the loop to its horizontal position, it is first swung out horizontally, and its extremities then allowed to slip downwardly in the pockets 105 of the strap members 1, so that the lugs 8 are engaged behind the retaining members 9. The engagement of the lugs 8 between

the side of the car and the retaining members 9, holds the loop in its horizontal position.

In the form illustrated in Figs. 4 and 6, 5 the major portion of the loop member 6 is of round bar material, but its extremities are flattened and broadened so that their height is greater than their thickness, conforming in this particular to the general shape of 10 the extremities 7 of the loop in Figs. 1 and 2. This form shown in Figs. 4 and 6 has the ends 10 bent forwardly in the general plane of the loop member 6 to form stops which operate to prevent lateral shifting of the 15 loop.

The form illustrated in Fig. 4 has an auxiliary loop 11 mounted in a lower pocket 12 of the strap member 1 and connected to the loop member 6 by means of a suitable 20 link 14.

The form illustrated in Figs. 7 and 8 has bracket members 1' formed with the horizontally disposed supporting portions 1^a directed inwardly, and the pockets 1^b having the upper walls 1^c. The extremities of the supporting portions 1^a are directed rearwardly to provide hangers 1^d. The loop member 6 has its side portions or legs diverging and terminating in the extremities 30 7 which are adapted to fit within the pocket 1^b and contact with the top walls 1^c thereof when the leg portions are resting on the top of the supports 1^a. In this form, the loop is folded to its vertical position by swinging 35 it upwardly so that the extremities 7 are moved downwardly out of the pockets 1^b, in which position the loop is supported vertically against the side of the car upon the hangers 1^d. To move the loop to its horizontal position, it is lifted vertically until 40 the extremities 7 engage in the pockets 1^b, and then allowed to swing out horizontally.

In the form illustrated in Figs. 10 and 11, 45 the strap members 1 have the inwardly directed flanges 15 which lie in the general vertical line of the leg portions of the loop 6. The loop is formed of bar material, and has outwardly directed extremities. The strap members 1 are formed with a single 50 pocket of depth somewhat greater than twice the diameter of the extremities of the loop. The upper wall of the pocket is removed from the top of the flanges 15 by a distance approximately equal to the diameter 55 of the loop. When the loop is in its horizontal position, the extremities engage the top wall of the pocket, and the legs are supported upon the top of the flanges 15. The loop is folded into its vertical position 60 by swinging it upward until the legs thereof can clip downwardly behind the flanges 15. When the extremities of the loop are then moved downward to the bottom of the pockets, the loop will be held in its vertical position by the flanges 15. In the form

illustrated in Fig. 9, the loop 6 has forwardly directed stops 6^a and the strap members have outwardly directed flanges 16. In this form, the loop is made of bar material and the pockets of the strap members 1 have 70 a depth of substantially four times the diameter of the extremities 7. When the loop member is folded downwardly, the stops 6^a can slip behind the flanges 16, but when the loop is lifted above the flanges and 75 swung outwardly to its horizontal position, the stop members 6^a will rest on top of the flanges 16 and support the loop in its horizontal position.

In all of the foregoing forms, it will be 80 seen that the loop member is shiftable from one level to another, and is adapted at one of these levels to be supported by the strap members in its outfolded or horizontal position, and in the other of said levels is permitted to occupy its vertical or infolded position.

In the forms illustrated in Figs. 1 to 6 inclusive, the portions of the loop adapted to engage the strap members are more extensive transversely of the general plane of the loop than they are in the plane of the loop, and by virtue of this feature, the loops are adapted to be supported in their horizontal position. 95

In the forms illustrated in Fig. 7 to 11 inclusive, the width of the strap members is varied to provide a support for the loop in its horizontal position, and a retaining means therefor when the latter is in its vertical position. 100

I am aware that other modifications involving the essential features of my invention may be made, and therefore, I do not intend to limit my invention to the specific 105 forms shown.

What I claim is:

1. A stake pocket comprising strap members adapted for attachment to the side of a car, a loop member supported by said strap members and adapted to embrace a portion of a stake, the strap members being formed with portions adapted to support said loop member in a horizontal position and portions adapted to support the loop member in 110 a vertical position, said loop member being movable in a vertical direction into engagement with one or the other of said portions of the strap members. 115

2. A stake pocket comprising strap members adapted for attachment to the side of a car, a loop member supported by said strap members and adapted to engage a portion of a stake, said strap members including portions adapted to coöperate with the side of the car to support said loop in horizontal position and portions adapted to coöperate with the side of the car to support said loop in a vertical position, said loop being movable vertically relative to the strap members 120 125 130

for engagement with said different portions thereof.

3. A stake pocket comprising strap members adapted for attachment to the side of a car, a loop member adapted to engage a stake and supported by said strap members, said strap members having portions adapted to support said loop in a vertical position and portions adapted to support the same in a horizontal position, said portions being vertically removed from each other, and said loop member being movable vertically into engagement with either thereof.

4. A stake pocket comprising strap members adapted for attachment to the side of a car, a loop member adapted to engage a stake and swingingly supported by said strap members, said loop member being arcuately movable from an infolded to an outfolded position and vertically movable relative to the strap members for the purpose of securing it in its outfolded position.

5. A stake pocket comprising strap members adapted for attachment to the side of a car, and provided with a horizontal retaining face and a vertical retaining face, and a loop member swingingly supported by said strap members and movable into engagement

with said retaining faces selectively for the purpose of support in operative or inoperative positions, respectively.

6. A stake pocket comprising strap members adapted for attachment to a car, a loop member swingingly supported thereby, said loop member being movable vertically relative to the strap members to an operative position wherein it is fixed against downward arcuate movement.

7. A stake pocket comprising strap members, a loop member supported by said strap members, one of said strap members being formed with a portion adapted to support said loop member in a horizontal position, and a portion adapted to support the loop member in a vertical position, said loop member being movable in a vertical direction into engagement with one or the other of said portions of the strap member.

In testimony whereof I hereunto affix my signature in the presence of two witnesses, this 30th day of June, 1914.

JOHN M. ROHLFING.
